HYPODERMIC SYRINGE CONSTRUCTION

Arthur E. Smith, Los Angeles, Calif.

Application March 24, 1941, Serial No. 384,879

7 Claims. (Cl. 128—218)

This invention relates to improvements in hypodermic syringe constructions.

The general object of the invention is to provide an ampule containing syringe including novel means for introducing a medicament into the liquid vehicle within the ampule.

Another object of the invention is to provide an ampule containing syringe wherein a medicament is introduced into the ampule after the ampule is positioned in the syringe.

A further object of the invention is to provide a novel syringe.

Other objects and advantages of the invention will be apparent from the following description taken in connection with the accompanying drawing wherein:

Fig. 1 is a central longitudinal section thru my improved syringe and ampule;

Fig. 2 is a fragmentary view similar to Fig. 1 of the upper end of the syringe and ampule showing the plunger rod out of engagement with the ampule stopper;

Fig. 3 is an enlarged fragmentary sectional view of the inner end of the plunger rod;

Fig. 4 is a side elevation of a syringe and ampule partly in section showing a modified form of my invention;

Fig. 5 is an enlarged fragmentary central sectional view thru the lower end of the syringe and ampule shown in Fig. 4; and

Fig. 6 is a view similar to Fig. 2 showing the modification.

Referring to the drawing by reference characters I have indicated my improved hypodermic syringe generally at 10. As shown the syringe 10 includes a barrel portion 12 closed at one end by a removable cap 13 which is threadedly received thereto as at 14. The opposite end of the barrel 12 is shown as closed by a fixed tip member 15 having a longitudinal reduced central aperture 16 therethru and including a reduced threaded needle receiving end 17. Intermediate the length thereof the barrel 12 includes a finger grip member 18. The cap 13 includes a telescopic ampule engaging member 19 having an enlarged head 20 thereon. A plunger rod 21 extends thru the cap 13 and the telescopic head 20 and has a palm engaging head member 22 thereon.

Surrounding the plunger rod 21 within the cap and telescopic member a coiled spring 23 is provided which resiliently urges the telescopic member 19 to an extended position. Adjacent the end thereof opposite the palm engaging member 22 the plunger rod 21 has an enlarged collar 24 se-

cured thereon and the end of the plunger rod is bevelled as at 25.

Opening thru the tapered end 25 the plunger rod is hollow forming a recess 26 therein on the side wall of which I provide a flat spring member 27 which includes an inwardly directed shoulder 28. Behind the spring 27 the wall of the recess 26 has a groove 29 therein to allow movement of the spring.

10 My invention is adapted for use in preparing solutions for injection and wherein the drug or medicament is kept from the vehicle such as distilled water until ready for use. To accomplish this a pellet 30 is positioned in the plunger rod recess 26 and is inserted to a position above the shoulder 28 of the spring 27 which acts to prevent the pellet 30 from becoming accidentally dislodged.

The end 17 of the syringe is adapted to receive 20 a standard type double ended hypodermic needle 31.

For use in the syringe 10 I provide an ampule which is indicated generally at 35. As shown the ampule 35 includes a hollow cylindrical glass body 25 portion 36 closed at the lower end by a rubber stopper 37 and at the upper end by a rubber piston stopper 38.

The stopper 37 has an enlarged flange 39 thereon which overlaps the adjacent end of the body 36. Opening thru the inner face thereof the stopper 37 has a recess 40 therein.

The stopper 38 is within the ampule body 36 and is spaced below the top thereof. The stopper 38 has a recess 42 therein opening thru the outer face thereof and a recess 43 therein opening thru the inner face thereof with a thin partition or diaphragm 44 between the two recesses.

Between the two stoppers 37 and 38 the ampule body is filled with a suitable medicament vehicle such as distilled water.

In use an operator preferably places the double ended needle 31 on the syringe end 17 and removes the cap 13 and inserts the ampule 35 into the syringe barrel 12. The operator then places 45 a pellet 30 in the recess 26 of the plunger rod and thereafter replaces the cap 13. As the cap 13 is replaced the head 20 of the telescopic member 19 engages the end of the ampule and forces it towards the tip 15. As the ampule is thus 50 moved the upper end of the needle 16 passes thru the stopper 37 into the recess 40 therein.

At the same time the end 25 of the plunger rod enters the recess 42 of the stopper 38 and upon continued movement pierces the partition 44 55 and enters the stopper recess 43 thus commu-

nicating with the interior of the ampule. When the end 25 of the plunger rod enters the ampule the vehicle therein contacts the pellet 30 and in that time completely dissolves it thus forming a freshly prepared solution.

To eject the fluid from the ampule 35 the operator moves the plunger rod 21 towards the tip 15 and the head 24 of the plunger rod forces the ampule stopper 38 towards the stopper 37 thereby forcing the fluid in the ampule into and thru the needle 31.

In Figs. 4 and 5 I have indicated a hypodermic syringe generally at 50 which is similar to the previously described syringe 10 and like portions thereof are indicated by similarly primed reference numerals. Furthermore within the syringe 50 I have shown an ampule 51 which is similar to the previously described ampule 35 and like portions thereof are indicated by similarly primed reference numerals.

Mounted on the threaded end 17' of the syringe 50 I provide an adapter member 52. As shown the adapter member 52 includes a body portion 53 and a reduced externally threaded end portion 54. Opening thru the end thereof the body 53 has a threaded recess 55 therein in which the threaded end 17' of the syringe is positioned.

Within the recess 55 and extending upward therefrom a predetermined distance I provide a hollow tube 56 which is fixedly mounted in the portion 54 of the adapter and the end of which is bevelled as at 57. Opening thru the threaded end 54 the adapter has a reduced aperture 58 therein which communicates with the interior of the tube 56. Surrounding the aperture 58 the end face of the threaded portion 54 is countersunk as at 59 to receive the bulbous portion of a double ended hypodermic needle 61 to be later described. Adjacent the tapered end 57 of the tube 56 a medicament pellet 62 is placed within the tube 56. The pellet 62 is cylindrical and has a diameter which is substantially equal to the interior diameter of the tube 56 so that the pellet is held in place by friction.

In operation after the adapter 52 is positioned on the end 17' of the syringe 50 and the double ended needle 61 is positioned on the adapter, the operator places the ampule 51 within the barrel of the syringe 50 and replaces the cap 13' which forces the ampule towards the tip 15' as previously described in connection with syringe 10. As the ampule 51 is thus moved towards the tip 15' the sharpened end 57 of the adapter tube 56 pierces the stopper 37' and enters the recess 40' whereupon the liquid vehicle in the ampule dissolves the medicament pellet 62.

Thereafter the freshly prepared solution within the ampule 51 may be discharged therefrom in the same manner as previously described in connection with the syringe 10 by moving the plunger rod 21' towards the tip 15' the head 24' of which forces the stopper 38' towards the stopper 37' thereby forcing the liquid into the adapter tube 56 and thence thru the double ended needle 61.

The plunger 24' has a plane lower face as shown in Fig. 6.

The needles 31 and 61 are held in place by cap members 31a and 61a which have threaded sockets 31b and 61b respectively which engage similarly threaded ends 31c and 61c on the syringe and adapter respectively. The needles 31 and 61 include soft metal balls 31d and 61d which are engaged by the ends 31c and 61c and by the cap members 31a and 61a to form a joint.

This type of needle mount is old in the art and forms no part of the present invention.

From the foregoing it will be apparent that I have provided a novel hypodermic syringe and ampule therefor which are simple in construction and highly efficient in use.

Having thus described my invention, I claim:

1. In a hypodermic syringe, an elongated barrel, an end member for each end of the barrel, an ampule in said barrel, said ampule having a cork in each end, and one of said end members having an inwardly projecting sharpened tube thereon, said tube being adapted to receive a medicinal pellet, the cork adjacent said one end member having a puncturable portion.

2. In a hypodermic syringe, a barrel, an end member for the barrel, an ampule in said barrel, said ampule having a cork in each end, one of said corks having a puncturable portion, said end member having a hollow cork piercing member projecting forwardly therefrom, and a medicinal pellet in said hollow cork piercing member.

3. In a hypodermic syringe, a barrel, an end member mounted on said barrel, an ampule in said barrel, said ampule having a puncturable piston cork therein at one end, a plunger slideable in the barrel to move the piston cork, said plunger having a hollow cork piercing member projecting forwardly therefrom and opening into the barrel and adapted to receive a medicinal tablet and a cork in the other end of said ampule.

4. In a hypodermic syringe, a barrel, an end member at each end of the barrel, an ampule in said barrel, said ampule having a cork in each end, one of said corks having a puncturable portion, one of said end members having a pointed member projecting forwardly therefrom and adapted to pierce said puncturable portion, said pointed member being adapted to receive a medicinal pellet and means on the pointed member to hold a pellet in place.

5. In a hypodermic syringe, a barrel, an end member, said end member and barrel having coacting threaded portions, an ampule in said barrel, said ampule having a cork in each end, one of said corks having a puncturable portion, a plunger slideable into the barrel, said plunger having a hollow pointed member projecting forwardly therefrom and adapted to pierce said puncturable portion, said hollow pointed member being adapted to receive a medicinal pellet and means on the hollow pointed member to hold the pellet in place.

6. In a hypodermic syringe, a barrel, an end member, said end member and barrel having coacting threaded portions, an ampule in said barrel, said ampule having a plunger cork slideable in one end thereof, said cork having a thin puncturable portion, a plunger slideable into the barrel, said plunger having a head thereon adapted to engage the plunger cork, a hollow pointed member projecting forwardly from said plunger head, said hollow pointed member being adapted to receive a medicinal pellet, and a leaf spring in said hollow pointed member and projecting into the hollow pointed member and adapted to engage a pellet in the hollow pointed member to hold the pellet in place and a cork in the other end of said ampule.

7. In a hypodermic syringe, a barrel, an end member mounted on each end of the barrel, a plunger movable through one of the end members, an ampule in the barrel, said ampule having a stopper in each end thereof, the other end member having a hole extending therethrough and

an adapter including a portion engaging the said other end member, said adapter having a tube therein extending through said hole and into the barrel, said tube having a forward end adapted to pierce one of said stoppers in said ampule, said tube being adapted to receive a medicinal pellet which has a diameter substan-

5 tially equal to the interior diameter of the tube so that the pellet is frictionally held in place, and said adapter having a portion at the forward end thereof engageable with a hypodermic needle, said adapter having a needle receiving hole therein.

ARTHUR E. SMITH.
